AIR CONDITIONING UNIT MOUNTING

Burdell S. Williams, Dayton, Ohio, assignor to
 Chrysler Corporation, Detroit, Mich., a corporation of Delaware

Application May 6, 1940, Serial No. 333,515

4 Claims. (Cl. 98—99)

The present invention covers an improvement in the art of air conditioning and has particular reference to means for mounting a window ledge air conditioning unit on the ledge of a window or other opening in order that the unit may be conveniently swung to one side when the window is opened for the purpose of permitting ingress and egress therethrough, especially in order that the outer surfaces of the window panes may be washed. The invention has particular utility with respect to the installation of air conditioning units of this character in tall buildings where a window unit, balanced on the window ledge when the window is open, constitutes a serious danger to life, not only of window washers attempting to straddle the unit or to climb over the unit to the window ledge, but to passers-by who might be struck down by an accidentally dislodged unit.

The principal object of the present invention is to provide means whereby a window ledge air conditioning unit of the character disclosed in the copending applications of Bernard W. Jewell, Serial No. 244,629, filed December 8, 1938, now Patent No. 2,198,500, Serial No. 303,968, filed November 13, 1939, and Serial No. 303,969, filed November 13, 1939, or my copending application, Serial No. 303,965, filed November 13, 1939, may be safely and firmly retained in position on a window ledge or other opening in the wall of an enclosure.

Another object of the present invention is to provide means whereby a unit of the window ledge type may be anchored in place in the position of use by means preventing the tipping of the unit from its position, which anchoring means constitutes means to permit swinging movement of the window ledge unit from its position of use to a position inside of the room in order that unhampered egress through the window may be permitted.

Another object of the present invention is to provide means having the foregoing advantages and characteristics and including a lifting device for raising the unit clear of the supporting window ledge in order that the unit may be swung inwardly into the room.

These and other objects and advantages of the present invention may be readily ascertained from the following specification and the accompanying drawings wherein like numerals refer to like parts throughout.

In the drawings,

Fig. 1 is an inside elevation of a portion of a wall and a window therein, an air conditioning

unit supported on the ledge thereof in the position of use and a preferred modification of the present invention applied thereto;

Fig. 2 is a vertical section through the construction of Fig. 1, taken substantially along line 2—2 of Fig. 1, and looking in the direction of the arrows;

Fig. 3 is a horizontal section through the construction of Fig. 1, taken substantially along line 3—3 of Fig. 1, and looking in the direction of the arrows;

Fig. 4 is a partial, vertical section, on an enlarged scale, taken substantially along line 4—4 of Fig. 2, and looking in the direction of the arrows;

Fig. 5 is a view similar to Fig. 1 showing a modified form of the invention;

Fig. 6 is a vertical section taken substantially along line 6—6 of Fig. 5, and looking in the direction of the arrows;

Fig. 7 is a view similar to Figs. 1 and 5, and showing another modification of the present invention; and

Fig. 8 is a view similar to Figs. 2 and 6, showing a side elevation of the construction shown in Fig. 7.

Figs. 1 to 4, inclusive, disclose a wall 10 having a window therein framed by the usual side frames 11 and 12, lintel 13, and ledge 14. The window opening is provided with an upper window 15 and a movable lower window 16 framed by sash members including the lower sash 17 of window 16. A window ledge air conditioning unit 20 is shown in position upon the ledge 14, the openings beneath the bottom sash 17 at the sides of the unit being blocked by side wings 21 and 22. The enclosure may be completed by lowering window 16 until sash 17 rests upon the tops of the unit 20 and the side wings 21 and 22, the movable window being preferably locked in position so as to assist in retaining the unit on the window ledge.

In order that positive retention of the unit and swinging movement thereof from the position of use may be accomplished, there is provided anchoring means comprising a post 25 pivotally attached to a member 26 fastened to or imbedded in the window ledge. The member 26 supports a box cam 27 on its upper surface which is fixed to post 25 and upon which rests the pivot portion of a supporting bar 28 pivotally retained on the post 25. The pivot portion of the bar 28 is free to rise vertically as forced by the cam 27 but is preferably retained from accidental dislodgment from the post by a cap 30 on the

top of the short post. The bar 28 extends beneath the bottom of the portion of the unit extending into the room as close to the window ledge as possible in order that the bar shall be as close to the center of gravity of the unit as possible. The member 26 may be attached to the post 25 as by riveting over a reduced portion of the post at 31 in order that the post may turn with respect to the member 26. A clevis 35 is preferably passed about the unit with its ends bolted to the bar 28 in order firmly to fasten the unit to the bar.

When the unit is in the position of use the side wing 21, which abuts the right side of the unit and the right side of the window opening, blocks the opening left between the unit and the window edges. This side wing may be fixed in position by screws fastened to the window ledge and sash guide as shown in Fig. 3. In order that the unit may be quickly moved to one side, a removable side wing 22 is preferably provided at the left side of the unit which may comprise a panel member 36 having its outer extremity slidably guided in the sash guides, and a panel member 37 having its inner edge slidably guided in a guide member 38 fastened to the left side of the unit. The members 36 and 37 may be retained in adjusted position as shown by bolts 39 fastened to member 36 and passing through slots 40 in member 37 and retained by wing nuts 41. Swinging of the unit is permissible after raising the movable window 16, sliding the side wing member 36 inward after loosening nuts 41 and removing the side wing 22.

In order that absolute stability of the unit may be provided during the swinging movement thereof and while it is in the position inside of the room as shown in skeleton outline in Fig. 3, means for supporting the weight of the unit are preferably provided, which means may comprise straps 45 fastened to a hook or pivot member 46 on the lintel 13 at the right side of the window and preferably substantially vertically above the post 25. The straps hang at the side of the window when the unit is in the position of use so as to be out of the way and unnoticeable. The lower extremity of each strap is provided with a hook 47 which is adapted to engage an eye 48 on the upper left edge of the unit, preferably retained thereon by bands 49 passing about the unit. The length of each strap is preferably such as to require lifting of the unit a short distance in order to engage the hooks 47 in the eyes 48 so that the bottom of the unit will clear the window ledge when the hooks are so engaged. This lifting of the unit is possible because of the loose, pivotal engagement of the bar 28 with the post 25 and may be accomplished by lifting the left side of the unit while turning the cam 27 as by means of the capstan lever 50 provided on the cap 30. When the unit has been so raised and the side wing 22 removed, the unit may be swung to the inner position where it will be supported until returned to the position of use.

A more rigid construction may be provided as by means of extending the pivot post upward as shown at 25' in Figs. 5 and 6, the vertical post being retained in position as by means of bolts 60 fastened into the wall construction.

Another modification is disclosed in Figs. 7 and 8, wherein vertical support is achieved by fastening a bar 28' and gusset member 61 firmly to an extended pivot post 62 rotatively retained in brackets 63 and 64 fastened to the wall construction beneath the window ledge 14 and supported

in a socket member 65 fastened to the floor. A clevis 35' may be fastened about the unit and bolted to the end of bar 28' and to the top of post 62 in order to firmly join the unit to the supporting structure. In this instance raising of the unit from the window ledge may be entirely accomplished by a cam member 66 inserted in the socket member 65 beneath the bottom of post 62 and which may be rotated by a bar 67 passing through a slot 68 in the side of the socket member. If desired, of course, a strap 45 and eye 48 may be provided.

In some instances the unit may be provided with adjustable supporting legs 70 extending from the unit to the outer surface of the window ledge in which case such legs should be so fastened to the unit as to be pivotally or otherwise movable to a position above the lowermost extremity of the unit. The unit may be provided with an air and noise deflecting hood 55 at its outer end which is accordingly preferably pivoted to the outer top edge of the unit by hinge members 56 in order that the hood may be swung back upon the top of the unit to lessen the length of the construction so that the unit may be swung through narrow windows. It may be seen, however, in Fig. 3 that the unit may be mounted in a window much narrower than the drawings suggest.

Having described several modifications of the present invention, it should be apparent to those skilled in the art that the same permits of various modifications in arrangement and detail. All such modifications as come within the scope of the following claims are considered to be a part of my invention.

I claim:

1. The combination with the wall of an enclosure having a window opening therein, of a window ledge air conditioning unit resting, when in use, on the lower edge of said window opening, and means associated with said wall and said unit for pivotally fastening said unit to said wall adjacent one side of said window opening whereby said unit may be swung from its position of use upon the lower edge of said window opening to a position inside of the room for permitting free egress and ingress through said opening comprising a pivot post mounted on the ledge of said window, a bar fastened to said unit and pivotally associated with said pivot post, and a cam rotatably mounted on said pivot post for raising said bar in order to permit swinging of the unit.

2. The combination with the wall of an enclosure having a window opening therein, of a window ledge air conditioning unit resting, when in use, on the lower edge of said window opening, and means associated with said wall and said unit for pivotally fastening said unit to said wall adjacent one side of said window opening whereby said unit may be swung from its position of use upon the lower edge of said window opening to a position inside of the room for permitting free egress and ingress through said opening comprising a pivot post mounted on the ledge of said window, a bar fastened to said unit and pivotally associated with said pivot post, a cam rotatably mounted on said pivot post for raising said bar in order to permit swinging of the unit, and a supporting member pivotally attached to the upper portion of said window opening above said pivot post and provided with means for engaging a portion of said unit remote from said pivot post.

3. The combination with the wall of an en-

closure having a window opening therein, of a window ledge air conditioning unit resting, when in use, on the lower edge of said window opening, and means associated with said wall and said unit for pivotally fastening said unit to said wall adjacent one side of said window opening whereby said unit may be swung from its position of use upon the lower edge of said window opening to a position inside of the room for permitting free egress and ingress through said opening comprising a pivot post mounted on the ledge of said window, a bar fastened to said unit and pivotally associated with said pivot post, a cam rotatably mounted on said pivot post for raising said bar in order to permit swinging of the unit, and a plurality of supporting straps pivotally attached to the upper portion of said window opening above said pivot post and provided with means for engaging a portion of said unit remote from said pivot post.

4. The combination with the wall of an enclosure having a window opening therein, of a window ledge air conditioning unit resting, when

in use, on the lower edge of said window opening, and means associated with said wall and said unit for pivotally fastening said unit to said wall adjacent one side of said window opening whereby said unit may be swung from its position of use upon the lower edge of said window opening to a position inside of the room for permitting free egress and ingress through said opening comprising a pivot post mounted on the ledge of said window, a bar fastened to said unit and pivotally associated with said pivot post, a cam rotatably mounted on said pivot post for raising said bar in order to permit swinging of the unit, and a plurality of supporting straps attached to the upper portion of said window opening above said pivot post and provided with means for engaging a portion of said unit remote from said pivot post, said straps being too short to engage said portion of said unit unless said portion of said unit is raised from the lower edge of said window opening.

BURDELL S. WILLIAMS.
